G. T. PEARSONS

FIRE EXTINGUISHER

Filed Sept. 9, 1916

UNITED STATES PATENT OFFICE.

GEORGE T. PEARSONS, OF NEW YORK, N. Y.

FIRE EXTINGUISHER.

Application filed September 9, 1916. Serial No. 119,215.

To all whom it may concern:

Be it known that I, GEORGE T. PEARSONS, a citizen of the United States, residing in the borough of Manhattan, in the city, county, and State of New York, have invented new and useful Improvements in Fire Extinguishers, of which the following is a specification.

This invention relates to syringes adapted for fire extinguishers in which pumping mechanism is provided in a cylinder or reservoir to create an air pressure in the reservoir and such air pressure utilized to eject a liquid contained in the reservoir, and it is the object of the invention to provide improved means to connect the pumping mechanism with the reservoir and means to seal the pumping mechanism from the liquid in the reservoir.

A further object of the invention is to provide improved intake means to the outlet of the reservoir to automatically connect the outlet to whichever end of the reservoir is in lowermost position when the syringe is in operation, and to provide valve mechanism to control the discharge of the liquid from the outlet and to shut off communication between the reservoir outlet and the reservoir.

Another object of the invention is to provide a syringe in which the reservoir has an extension of reduced width along its side in which the pumping mechanism is mounted, and a portion of larger dimensions to constitute the liquid carrying chamber of the reservoir.

In the drawing accompanying and forming a part of this specification Figure 1 is a sectional side elevation of a syringe showing an embodiment of my invention, the section being taken on the line 1—1 of Figure 2.

Figure 2 is a cross sectional view taken substantially on the line 2—2 of Figure 1 and looking in the direction of the arrows.

Figure 3 is a sectional side elevation of the piston chamber taken substantially on the line 3—3 of Figure 2; and

Figure 4 is a detail view of the operating handle.

Similar characters of reference designate like parts throughout the different views of the drawing.

In the embodiment of the invention shown

in the drawing I provide a tank or reservoir for a fire extinguishing liquid, such as carbon tetrachloride, said reservoir comprising a body portion 3 substantially of the shape shown in cross section, provided with an extension of reduced width 4 extending longitudinally of the side of the body portion in which the pumping mechanism is located, and the larger portion to constitute what is herein termed the liquid carrying portion of the syringe, and the ends 5 and 6 secured thereto, as by soldering or otherwise, the end 5 having a discharge outlet 7 and a filler opening closed by a plug 8.

A pumping mechanism, as stated, is mounted in the reduced portion 4 of the reservoir to be outside of the enlarged or liquid carrying chamber to create an ejecting fluid pressure in the reservoir to forcibly eject the fire extinguishing liquid from the reservoir, and consists of a piston chamber or cylinder 7' connected at opposite ends to heads 9 and 10, the head or end 10 abutting against the reservoir end 6 and the bore therein being of the same diameter as the inside diameter of the cylinder 7' and extending through said head 10 to register with an opening of the same diameter in the reservoir end 6. The outer end of the bore is internally screw threaded for the engagement of a flanged perforated nut 11. The engagement of the nut in said head 10 clamps the reservoir end between the flange of the nut and the head 10 thereby securing the piston chamber to said end and supporting it therefrom. The piston chamber with its connected heads is of less length than the length of the reservoir. Each of the heads 9 and 10 has a laterally projecting portion 12 and 13 having ports 14 and 15 communicating with the piston chamber, and the port 15 communicates with a chamber 16 having an inlet exterior of the reservoir, which inlet is closed by a plug 17 having a spring influence check valve opening into and closing outward from said chamber. A tube 18 is secured at its ends in the cylinder head extensions 12 and 13 and connects port 14 with the air inlet chamber 16. The cylinder head projections 12 and 13 lie adjacent the wall of the reduced portion of the reservoir at the junction of said reduced portion with the reservoir portion of enlarged diameter, and the

ports 14 and 15 therein are closed by spring influenced valves 19 and 20 closing outward from and opening into the piston chamber.

Air is drawn alternately through the ports 14 and 15 to the opposite ends of the piston chamber by a piston 21 having suitable packing, reciprocated in the piston chamber by a rod 22 extending through an opening in the nut 11 and a stuffing box 23 carried by said nut to the exterior of the piston chamber and reservoir, and having an operating handle 24 connected thereto.

To eject the air which is alternately drawn to the opposite ends of the piston chamber 15 into the reservoir the head 9 has a chamber 25 which has a port 26 communicating with outlet means in the form of a tubular member 27 connected at one end to the head 9 and having an outlet 28 into the reservoir in 20 the opposite end, with a tube 29 secured in said outlet and extending into the chamber 27 to a point adjacent the head 9, said tube having a spring influenced check valve 29' opening outward from and closing into the chamber 27 to preclude the entering of liquid from the reservoir into said chamber when the extinguisher is not in use. In line with the port 26 is a port 30 leading into the end of the piston chamber to constitute an 25 outlet for said chamber, said port being normally closed by a spring influenced valve 31 closing into the piston chamber and opening outward therefrom. The chamber 25 is located in a lateral extension 32 of the cylinder head 9 and has a port 33 communicating with chamber 25. A port 33' in a lateral extension 32' of the opposite head 10 of the piston chamber communicates with the piston chamber to constitute an outlet for 30 the opposite end of said chamber, communication between said port and the piston chamber being controlled by a spring influenced valve 34 closing into the piston chamber and opening outward therefrom. The port 33' is connected to the chamber or casing 25 through the port 33 by a tube 35. By the provision of the tube 29 the air in the chamber 27 will counteract the weight of the liquid in the reservoir preventing entrance of liquid into said chamber, and thus sealing the pumping mechanism from the liquid in reservoir. The piston 21 separates the cylinder 7 into two compartments.

To shut off the expelling fluid pressure from the discharge outlet 7 intake means operated by gravity are provided for connecting the outlet of the reservoir with the liquid in the reservoir near the side as well as the end of the reservoir which is lowermost in all positions of the reservoir. For this purpose a tube 36 is secured at one end to the nozzle in which the outlet of the reservoir is located, which tube extends toward the end 6 of the reservoir opposite and remote to the discharge outlet with the end of

the tube engaging in a chamber 37 secured to the end 6 of the reservoir by a flanged nut 38 passing through an opening in the reservoir end 6 and internally threaded into the chamber 37. An intake tube 39 extending longitudinally of the enlarged or liquid carrying portion of the reservoir is connected to the chamber 37 by a coupling 40 mounted to have rotative movement through a complete circle on a tube 42 in fluid connection with the chamber 37. Communication of the coupling with the chamber 37 is through lateral ports 41 in the tube communicating with an annular portion 43 of the coupling. The outer end of the tube 42 is closed by a cap 44, and through which cap and a stuffing box carried thereby the tube 36 extends. To seal the coupling there is interposed between the ends of the coupling, the cap 44 and the boss 38, a suitable packing, as shown at 45. With the pumping mechanism located in the reduced portion of the reservoir it will be obvious that the intake tube 39 will rotate or revolve around the tube 42 in a complete arc of a circle and will fall by gravity to assume a position diametrically below the axis of rotation of the intake tube 39 and opposite that portion of the side of the reservoir which is lowermost no matter what the position of the syringe may be.

To connect the reservoir outlet with the liquid in the reservoir adjacent the end which is lowermost with the discharge outlet of the syringe tilted upward or downward from the horizontal, valve mechanism is provided to automatically shut off the inlet to the tube 39 which is uppermost from the outlet 7 and connect the lowermost inlet to the tube 39 to the outlet 7, said valve mechanism comprising a pair of valves 46, to co-operate with valve seats connected to or formed in the ends of the tube 39, and said valves being connected by a rod 47 of greater length than the tube 29 and extending therethrough so that when one of the valves is seated the other will be unseated.

To seal the outlet 37 to prevent leakage and evaporation of the liquid and to permit of the creating of an air pressure in the reservoir by the pumping mechanism to be utilized to eject the liquid from the reservoir, I provide a valve 48 having screw threaded connection with a stem 49 extending through a stuffing box in the nut 38 to the exterior of the reservoir with means connected thereto to rotate the stem. It will be obvious that by rotating the stem in one direction the valve will be seated against the end of the tube 36 and by rotating it in a reverse direction the end of said tube will be opened to the chamber 37 and through said chamber and the tube 39 connected thereto with the liquid in the reservoir.

To lock the piston against movement when

the syringe is not in use the operating handle 24 has a cap or concaved portion 50 to straddle the nut 11, and has opposite cam slots 51 for the engagement of pins 52 projecting laterally from the nut 11.

Having thus described my invention I claim:

1. In a syringe, the combination of a reservoir to contain a liquid and having a discharge outlet; an air pump in the reservoir having an outlet; a chamber connected to the pump outlet and an outlet tube for said chamber extending into said chamber from the end opposite to its connection with the pump outlet, substantially as and for the purpose specified.

2. In a syringe, the combination of a reservoir to contain a liquid and having a discharge outlet; a piston chamber in said reservoir having an outlet; a piston to reciprocate in the piston chamber; a suction air inlet to the piston chamber from the exterior of the reservoir; a chamber connected to the outlet of the piston chamber and having an outlet leading into the reservoir; a tube connected to the outlet of and extending into said chamber, and a spring influenced valve at the outlet end of said tube opening outward from and closing into the chamber, substantially as and for the purpose specified.

3. In a syringe, the combination of a reservoir to contain a liquid and having a discharge outlet; a piston chamber in said reservoir having an outlet; a piston to reciprocate in the piston chamber; suction air inlets in the piston chamber to opposite sides of the piston from the exterior of the reservoir; and a chamber connected to the outlet of the piston chamber and having an outlet leading into the reservoir, substantially as and for the purpose specified.

4. In a syringe, the combination of a reservoir having an extension of reduced width along one side and a discharge outlet; pumping mechanism located in the reduced portion of the reservoir to pump air into the reservoir; and an intake for the reservoir outlet having inlets adjacent the side and opposite ends of the reservoir and rotatable through a complete circle on an axis coaxial with the reservoir outlet and unobstructed in its movement by the pumping mechanism substantially as and for the purpose specified.

5. In a syringe, the combination of a reservoir having a discharge outlet; an air pump in the reservoir having an outlet and located at the side of the reservoir; a chamber connected to the outlet of the pump and having an outlet leading into the reservoir; and an intake tube connected to the reservoir outlet extending longitudinally of the reservoir with its ends adjacent the side and opposite ends of the reservoir and rotatable

on an axis located centrally of the reservoir, substantially as and for the purpose specified.

6. In a syringe, the combination of a reservoir having a discharge outlet at one end of the reservoir; an air pump having an outlet in the reservoir; a tube fixed at one end in the reservoir outlet and extending longitudinally of the reservoir with its free end adjacent the end of the reservoir opposite to the discharge outlet; and a tube extending longitudinally of the reservoir with its ends adjacent the side and opposite ends of the reservoir connected to the tube fixed in the reservoir outlet to revolve on an axis in line with the axis of said latter tube, substantially as and for the purpose specified.

7. In a syringe, the combination of a reservoir having a discharge outlet at one end of the reservoir; an air pump having an outlet in the reservoir; a tube fixed at one end in the reservoir outlet and extending longitudinally of the reservoir with its free end adjacent the end of the reservoir opposite to the discharge outlet; a tube extending longitudinally of the reservoir with its ends adjacent the side and opposite ends of the reservoir connected to the tube fixed in the reservoir outlet to revolve on an axis in line with the axis of said latter tube; and a valve operable from the exterior of the reservoir to close the free end of the tube fixed in the reservoir outlet, substantially as and for the purpose specified.

8. In a syringe, the combination of a reservoir having an extension of reduced width along one side and a discharge outlet at one end of the enlarged portion of the reservoir; an air pump in the extended portion of the reservoir having an outlet leading into the reservoir; and an intake tube for the discharge outlet of the reservoir extending longitudinally of the reservoir with its ends adjacent opposite ends and the side of the reservoir and rotatable on an axis coaxial with the reservoir outlet, substantially as and for the purpose specified.

9. In a syringe, the combination of a reservoir having a discharge outlet; an air pump in the reservoir having air inlet suction means to opposite ends thereof from the exterior of the reservoir; outlet means from opposite ends of the pump into the reservoir; and valves to shut off communication between said suction inlets and pump and the outlet means and the reservoir substantially as and for the purpose specified.

10. In a syringe, the combination of a reservoir for a liquid and having a discharge outlet; a piston chamber in the reservoir having outlets from opposite ends thereof; a piston to reciprocate in said chamber; air suction means to opposite ends of the piston chamber from the exterior of the reservoir; an air chamber connected at one end to the

outlets of the piston chamber and having an outlet leading into the reservoir at the opposite end; and means in said chamber operable to prevent the flow of liquid from the reservoir to said chamber, substantially as and for the purpose specified.

11. In a syringe, the combination of a reservoir having an extension of reduced width along one side thereof to constitute a pump carrying chamber, and the enlarged portion of the reservoir constituting a liquid carrying chamber having a discharge outlet; an air pump mounted in the pump carrying chamber, said pump having an outlet leading into the reservoir; and intake means rotative through a complete circle connected to the discharge outlet of the reservoir, substantially as and for the purpose specified.

12. In a syringe, the combination of a reservoir having an extension of reduced width along one side thereof to constitute a pump carrying chamber, and the enlarged portion of the reservoir constituting a liquid carrying chamber having a discharge outlet; an air pump mounted in the pump carrying chamber, said pump having an outlet leading into the reservoir; and an intake tube connected to the discharge outlet, said tube extending longitudinally of the liquid carrying chamber with its ends adjacent the side and opposite ends of said chamber, substantially as and for the purpose specified.

13. In a syringe, the combination of a reservoir having an extension of reduced width along one side thereof to constitute a pump carrying chamber, and the enlarged portion of the reservoir constituting a liquid carrying chamber having a discharge outlet; an air pump mounted in the pump carrying chamber, said pump having an outlet leading into the reservoir; and a tube extending longitudinally of the liquid carrying chamber with its ends adjacent the side and opposite ends of said chamber, said tube being connected to the discharge outlet and rotatable on an axis centrally of the liquid carrying chamber, substantially as and for the purpose specified.

14. In combination with a reservoir having an outlet, a pump comprising a piston, a cylinder in which said piston is arranged to reciprocate and divided by said piston into two compartments, a valved air inlet to each of said compartments, means to connect said air inlets with an air inlet from the exterior of the receptacle and outlet means to alternately connect the piston cylinder at opposite sides of the piston with the reservoir; to discharge the air from the compartments at opposite sides of the piston into the reservoir during the reciprocation of the piston, substantially as and for the purpose specified.

15. The combination with a reservoir having an outlet, of a pump in the reser-

voir comprising a cylinder, a piston to reciprocate in said cylinder and divide the cylinder into two compartments, a valved air inlet to each of said compartments, means to connect said air inlets with an air inlet from the exterior of the reservoir, a casing having an outlet leading into the reservoir and a port leading to one of the cylinder compartments, a valve movable in said casing in a direction longitudinally of the pump cylinder and controlling the opening and closing of said port, and a valved connection leading from the other cylinder compartment to said casing for the purpose specified.

16. In a syringe, the combination with a reservoir having an outlet, of a cylinder therein of less length than the reservoir and having a connection at opposite ends to the exterior of the reservoir; outlets at opposite ends of the cylinder; means to which said outlets are connected to connect said outlets with the reservoir; a piston to reciprocate in the cylinder; and a rod to reciprocate the piston from the exterior of the cylinder and reservoir, and said piston during the reciprocation thereof alternately drawing air to opposite ends of the cylinder, and alternately discharging the air from the opposite ends of the cylinder through the cylinder outlets into the reservoir, substantially as and for the purpose specified.

17. In a syringe, the combination with a reservoir having an outlet, of a cylinder therein connected at opposite ends to the exterior of the reservoir; an outlet at one end of the cylinder; an outlet at the opposite end of the cylinder; a casing to connect said outlets with the reservoir; and a piston to reciprocate in the cylinder, substantially as and for the purpose specified.

18. In a syringe, the combination with a reservoir having an outlet, of a cylinder therein; air intakes at opposite ends of the cylinder to connect the cylinder to the exterior of the reservoir; valves in said intakes opening into the cylinder and closing outward therefrom; a valved outlet port in one end of the cylinder leading into the reservoir; a valved outlet port in the opposite end of the cylinder; means to connect said latter port to the cylinder port connected with the reservoir; and a piston to reciprocate in the cylinder, substantially as and for the purpose specified.

19. In a syringe, the combination with a reservoir having an outlet, of a cylinder therein having a head at each end and by means of one of which heads it is mounted and supported in the reservoir; an air intake to the cylinder in each head to connect the cylinder with the exterior of the reservoir; valves for said inlets opening into the cylinder and closing outward there-

from; an outlet port in one head of the cylinder; a valve in said port closing into the cylinder and opening outward therefrom; a chamber connecting said port with the reservoir; an outlet port in the opposite head of the cylinder; a valve in said port closing into the cylinder and opening outward therefrom; a tube exterior of the cylinder to connect said latter port with the port in the opposite head connected with the reservoir; and a piston to reciprocate in the cylinder, substantially as and for the purpose specified. 10

GEO. T. PEARSONS.
